UNITED STATES PATENT OFFICE

137,994

DESIGN FOR A WHISKEY GLASS, OR SIMILAR ARTICLE

Albert F. Mason, Morgantown, W. Va.

Application January 11, 1944, Serial No. 112,210

Term of patent 7 years

(Cl. D36—8)

To all whom it may concern:

Be it known that I, Albert F. Mason, a citizen of the United States, residing at Morgantown, in the county of Monongalia, and State of West Virginia, have invented a new, original, and ornamental design for a Whiskey Glass or Similar Article, of which the following is a specification, reference being had to the accompanying drawing, forming part thereof.

Figure 1 is a side elevational view of a whiskey glass, or similar article, showing my new design; and

I claim:

The ornamental design for a whiskey glass or similar article, as shown.

ALBERT F. MASON.
